ARITHMETICAL BINGO GAME APPARATUS

Ardis G. Sanders, Fowler, Ind.

Application January 17, 1955, Serial No. 482,149

1 Claim. (Cl. 273—135)

This invention relates to a game and it is particularly concerned with an arithmetical game. The main objects of the invention are to provide a game which will have educational value in the science of arithmetic; to provide such a game which will embody an element of chance whereby entertainment value is increased; to provide such a game which may be played by any desired number of competing players subject only to the provision of suitable numbers of playing boards and associated equipment for playing the game; to provide a game of the character indicated which will be appealing to both young and old players; and in general, it is the object of the invention to provide an improved game of the character indicated.

Other objects and advantages of the invention will be understood by reference to the following specification and accompanying drawing wherein there is described and illustrated a selected embodiment of the game.

In the drawing:

Fig. 1 is an illustration of a set of playing boards forming part of the equipment for playing the game; and

Fig. 2 is a perspective illustration of a portion of a set of number blocks forming another part of the equipment for playing the game.

The playing boards represented in Figure 1, are, in this instance, four in number being respectively designated 15, 16, 17 and 18, and they are preferably identical to each other in order that all players, each being furnished with one board, will compete with one another under like conditions so far as the playing boards are concerned. However, for some purposes playing boards may differ from each other.

The playing boards represented in Figure 1 are approximately of square form and they are suitably divided into squares or spaces as by printed lines represented at 19, which extend vertically and horizontally of the board. In this example, the boards are divided into 36 spaces. This division of the playing board results in the formation of six horizontal rows of spaces, six vertical rows of spaces, and two diagonal rows of spaces which respectively extend between the opposite corners of the playing board.

One of the diagonal rows of spaces is designated by the arrow-headed line marked 1. The horizontal rows of spaces are designated by arrow-headed lines marked 2, 6, 8, 10, 12 and 3, reading from the top to bottom of the playing board. Similarly, the vertical rows of spaces are designated by arrow-headed lines marked 4, 7, 9, 13, 11 and 5, reading from left to right of the playing board.

Each space is provided with an arithmetical sign such as a plus or addition sign 20, a minus or subtraction sign 21, a division sign 22, or a multiplication sign 23. The specific arrangement of these arithmetical signs or indicia is not critical and may be varied from that illustrated, but it has been found that the illustrated arrangement is very satisfactory.

For use in association with the playing boards, there is a set of number blocks 24 (Fig. 2) which, for a game

2

for four players, preferably consists of 144 separate number blocks comprising blocks or squares numbered as follows: twelve zeros, twelve ones, sixteen twos, sixteen threes, eighteen fours, eighteen fives, sixteen sixes, twelve sevens, eight eights, eight nines, and eight special blocks or jokers which are adapted to be used for any number at the option of the player who gains possession of such a special block. Figure 2 illustrates only a portion of the described set of blocks.

10 The playing boards 15 to 18 inclusive and the number blocks 24 may be made of any suitable material such as paper or fiber board of a grade selected in accordance with the durability which it is desired to build into the parts.

15 The game is played by supplying each player with one of the playing boards 15, 16, 17 or 18. The set of number blocks 24 are preferably arranged face down on a table or in a container such as a part of the box in which the game may be supplied to the purchaser. A 20 single game consists of thirteen plays successively made according to the numerical order of the rows 1 to 13 inclusive. To start playing, each player is furnished a playing board and then draws from the stock pile of number blocks, six blocks which are then turned face up 25 so that the players may see what numbers they have drawn. The first play is to be made on the diagonal row 1 and the players arrange their numbers in the spaces along said row 1 in such a manner that when the numbers contained in the row are added to each other, multiplied or subtracted as indicated by the indicia 20, 21, 22 and 23, the highest possible score will be attained for the row. For example, if the numbers 1, 4, 6, 0, and 7, and a special number block or joker are drawn and arranged in the manner indicated in dotted lines in Figure 1, the score for row 1 would be computed as follows: 1+4=5; 5×6=30; 30-0=30; 30×7=210; and assuming that the joker is played as a nine, 210×9=1890, the latter being the total score for the row.

30 For the next play on row number 2, each player draws five number cards and arranges these to the best advantage in the then unoccupied spaces in row number 2. The number 1 previously played in one square in the playing of a row 1, is counted as a part of row 2. For example, if the five number blocks drawn for the second play are 2, 5, 7, joker and 8, and if these are placed on the board in the manner indicated in Figure 1, the score for column 2 would be 1-2=-1; -1+5=4; 4+7=11; 11-the joker played as a zero =11; and 11+8=19, the latter being the total score for row 2.

35 It will be seen that considerable judgment may be exercised in the use of the special number blocks or jokers. In the illustrated arrangement in column 2, the joker was used as a zero in order to avoid lowering the score produced by the preceding numbers. When row 50 11 is played, the zero number applied to the joker in play 2 remains as the value of that block and will not lower the score produced by the other numbers of the row.

The playing of rows 11 and 13 does not require the drawing and placement of any number blocks, all 55 spaces having been filled as an incident to the playing of preceding rows. Hence, the playing of said rows 11 and 13 involves only the computation of the score on the basis of such previously placed number blocks. For the playing of the successively numbered rows, number blocks are drawn from the pool or stock pile of numbers, only 60 as many as are required to fill unoccupied spaces in the row being played and it is preferred that all players simultaneously play like numbered rows although this is not essential.

65 In the blind picking of the number blocks from the stock pile, there is, of course, an element of chance introduced into the game and each player's set of numbers

for each row will usually differ from the set of each of the other players so that the scores made by the respective players may vary considerably for like rows. A further element of chance occurs as an incident to the use of the same number block in two rows.

Certain rules may be made to induce the players to arrange numbers in a certain order. For example, one rule may be that a bonus of say 1,000 points shall be awarded a player for playing three number blocks with the same number in sequence in a row and the joker may be made available to represent say one of such three numbers. The playing of like number blocks in sequence to obtain the bonus score will usually be advantageous even though the arithmetical result in particular row is not necessarily the best that could be obtained with the numbers available for placement in the row. For example, if the three numbers which are placed in sequence in a row happen to be the number 1, no advantage would be gained by having such number 1 in a space marked with a multiplication sign 23 whereas substantial advantage might have been gained by placing a higher number in such a square. In this respect, there is an element of judgment as well as of chance introduced into the game. A larger bonus say 1,500 points may be awarded to a player who has used the same number four times or more in sequence in one of the rows, using not more than two jokers to represent the number in such sequence. Similarly, a bonus may be awarded to the player who has played four jokers in sequence in a row regardless of what number they originally represented. The award of bonuses may, if desired, be limited to a single bonus on any given number, or the award may allow two or more bonuses for the use of the same number in crossing sequences in which a number is common to the crossing sequences. For example, sequences in the diagonal row 1, vertical row 9 and horizontal row 8 might be based on a number such as the number six which is represented in the space common to these three rows. The number of bonuses which may be secured in one game based on different number sequences, may be unlimited. Other rules in this respect may, of course, be made.

Another rule which may be established is that if a sum cannot be divided evenly by a number placed in a square or space bearing a division sign (rows 6, 8, 9 and 13), the answer to that part of the play shall be regarded as zero and remainder of that particular play figured from that point. For example, if in play 9, the second square from the top has a number 2 placed in it, which is not an even divisor for the number 5, the computation for the first and second squares in play 9 would result in zero which multiplied by the 6 appearing in the next lower square

would still give a zero. Hence, substantial losses may be experienced where the divisor does not enter evenly into the dividend.

A game may consist in the completion of all of the 5 thirteen rows or plays indicated on the boards or of any selected number thereof and the score may be the total of the scores of the thirteen plays or the selected portion thereof. For only two players, it is preferred that only one-half of the number blocks be used, one-half of the number of each number being removed. For more than four players, additional playing boards and number blocks are provided to maintain approximately the indicated ratio of number blocks to playing boards.

In some instances, the arithmetical indicia 20, 21, 22 and 23 may be placed on the number blocks instead of on the playing board squares and in some instances, indicia may be omitted from one or more spaces (or blocks) and the player given freedom to use the number in any selected manner. Other variations may also be made 20 while retaining the principles of the game as described.

I claim:

A game comprising a set of like playing boards and a set of number blocks, the playing boards each having markings thereon defining a plurality of spaces each of which is adapted to receive one of the blocks of said set 25 of number blocks, said spaces being contiguously arranged in intersecting horizontal and vertical rows and at least one diagonal row, markings on said boards to indicate a sequence of use of said rows of spaces, said spaces being each provided adjacent a side thereof with arithmetical indicia of computations to be made with the numbers on the blocks placed in such spaces and aligned in the rows thereof, said blocks and spaces being so proportioned relative to each other that said number 30 blocks may be placed in said spaces to one side of the indicia therein so as to maintain visibility of said indicia when the number blocks occupy the spaces, said set of number blocks comprising a sufficient number of blocks to occupy all of the spaces on said set of playing boards, said set of blocks embodying groups thereof respectively having different numbers thereon, and another group 35 having marking thereon distinguishing the same from the blocks of said plurality of groups and adapted to be used at the option of the players for any selected number.
